NEON SIGN

Thomas Henry Boland and Richard Clifton Arnold, Haverhill, Mass.; said Arnold assignor to said Boland

Application January 29, 1937, Serial No. 122,939

2 Claims. (Cl. 40—130)

This invention relates to neon signs and has for its object a construction which adapts neon signs for uses for which, heretofore, they have been unsuitable.

5 A neon sign is brilliant and attractive and, consequently, has displaced other types of illuminated signs to a large extent where illuminated signs of a more or less permanent character are desired. Thus, neon signs are used commonly by stores, restaurants and the like, to display in brilliant illumination the name and general character of the establishment.

In such signs, a single neon tube or unit often forms the entire wording and in other cases two or more units are employed, each of which form a word or group of letters. Neon units are operated with high voltage and the conductors leading to and between each unit must be carefully insulated or maintained at least 1½" from any un-insulated object. Consequently, these signs have been constructed at the factory as permanent signs, the wording of which could not be changed except by return to the factory for reconstruction. Consequently, their field of use has been restricted.

30 The present invention contemplates a neon sign construction, such that the copy or wording can be changed at will merely by interchanging neon units and adjusting the position of the units to obtain proper spacing between letters and words. Thus, the invention makes practical the use of neon signs for advertising daily specials which may differ from day to day. It also makes possible the use of neon signs by theatres where the entertainment is changed weekly or more often.

35 The invention will be more clearly understood from the following description in conjunction with the accompanying drawing, in which:

40 Fig. 1 is a plan view of a sign embodying the invention and having the neon tubes removed;

Figs. 2 and 3 are sectional views taken upon the lines 2—2 and 3—3 respectively of Fig. 1;

45 Fig. 4 is a fragmentary plan view of a modified construction; and

Fig. 5 is a fragmentary longitudinal sectional view of the structure shown in Fig. 4.

Before explaining in detail the present invention it is to be understood that the invention is not limited in its application to the details of construction and arrangement of parts illustrated in the accompanying drawing, since the invention is capable of other embodiments and of being practiced or carried out in various ways. Also 50 it is to be understood that the phraseology or

terminology employed herein is for the purpose of description and not of limitation, and it is not intended to limit the invention claimed herein beyond the requirements of the prior art.

One structure embodying the invention is illustrated in Figs. 1, 2 and 3 of the accompanying drawing and comprises a support 10 which, as shown, is a hollow elongated casing formed of sheet metal. The top of the casing 10 is provided with a longitudinally extending opening 11 at the edges of which the sheet metal is folded to provide guide ways 12 and 13. A plurality of neon units 15, 16, 17 and 18 are carried by the support 10 and each comprises a pair of sockets 20 and 21 and a neon tube 22 having an electrode 23 at each end adapted to be detachably received in the sockets 20 and 21. Each of the sockets 20 and 21 is of similar construction and comprises a cup 25 of porcelain or other insulating material. The cup 25 is provided with ears 26 projecting outwardly therefrom and which are secured to a plate 27 by screws 28. The plate 27 is provided with an opening through which the upper end of the cup 25 projects. The ends of the plate 27 slidably engage the grooves 12 and 13 whereby the positions of the sockets 20 and 21 may be adjusted in the longitudinal direction of the structure. A U-shaped spring contact 30 is secured within the cup 25 by a screw 31 passing through the bottom of the cup and held in place by a pair of nuts 32 which are threaded upon the outer end of the screw 31. The screw 31 serves as a binding post.

35 Posts 33 and 34 of porcelain or other insulating material are suitably secured within the casing 10 near opposite ends thereof. The posts 33 and 34 are provided at their inner ends with binding posts 35 and 36 respectively. One lead 37 from the secondary of a transformer 38 passes through a porcelain tube 39 fitted in an opening in the wall of the casing 10 and is connected to the binding post 35. The other lead 40 from the secondary of the transformer 38 passes through a porcelain tube 41 fitted in an opening in the casing 10 and is connected to the binding post 36.

40 A plurality of porcelain posts 45 are secured in spaced relation within the casing 10 near the bottom thereof by screws 46. A bracket having arms 47 and 48 is secured to the inner end of each of the posts 45 by a screw 50. The bracket arms 47 serve to support the lead 40 within the casing 10. A trough 52 of Bakelite or other insulating material extends longitudinally within the casing 10 below the sockets 20 and 21 of each of the neon units 15, 16, 17 and 18 and is supported upon 45 50 55

and secured to the bracket arms 48 by screws 53. A flexible conductor 55 in the form of a coil spring connects the binding post 35 with the binding post 31 carried by the socket 20 of neon unit 15. A similar flexible conductor 56 connects the binding post 36 and the binding post 31 carried by the socket 21 of neon unit 18. The binding posts 31 of sockets 20 and 21 of adjacent neon units are connected by similar flexible conductors 57.

In the sign illustrated each neon tube 22 forms a single letter of the sign. If it is desired to change the wording of the sign the neon tubes 22 are replaced by other neon tubes forming other letters. When this is done the relative positions of the neon tubes 22 must be changed by adjusting the position of the plates 27 in order to obtain the proper and desired spacing between the letters of the sign. The flexible conductors 55, 56 and 57 permit this adjustment of the letters while the insulating trough 52 effectively separates and insulates the conductors 55, 56 and 57 from adjacent uninsulated parts of the structure. It will be understood that the electrodes 23 at the ends of each of the neon tubes 22 may be spaced the same in all letters and in such case the sockets 20 and 21 of each of the neon units may be carried by the same plate 27. When the changed wording contains less letters than the former wording of the sign, the neon tube of the unused neon units may be replaced by a jumper or conductor connecting the sockets of the unit.

In the structure shown in Figs. 1, 2 and 3 the electrodes 23 are positioned parallel and in the same plane as the letters formed by the neon tubes. In certain instances, it may be desirable, for the purpose of economy or other reasons, to employ neon tubes 22' as shown in Fig. 4 in which the electrodes are positioned in different planes and at right angles to the plane of the letters formed by the tubes. In such a case the electrodes of different neon tubes may be spaced apart different distances and it may be desirable to adjust transversely of the structure the relative positions of the sockets which receive the electrodes. Thus, as shown in Figs. 4 and 5, the socket 20' extends through an opening 59 in the plate 27'. The surface of the plate 27' may be provided with knurled portions 60 adapted to be engaged by the knurled edges 61 of a U-shaped

plate 62 having an opening 63 for the passage of the upper end of the socket 20'. Bolts 64 pass through aligned openings 65 and 66 in the plates 62 and 27' respectively and are secured to the ears 26' on socket 20'. The heads 67 on bolts 64 normally engage the plate 62 and support the socket 20'. Springs 68 surrounding the bolts 64 are interposed between the ears 26' and the plate 27'.

In the construction shown in Figs. 4 and 5 the ends of the plates 27' carrying the sockets 20' slidably engage longitudinally extending guide ways 12' and 13' and are adjustable in the longitudinal direction of the structure. The sockets 20' are adjustable in a direction perpendicular thereto, or transverse of the structure, by lifting the plate 62 and the socket 20' against the action of the springs 68 and moving the socket to the desired position. The plate 62 is then released thereby permitting the spring 68 to hold the plate 62 in its normal position against the plate 27'.

We claim:

1. A neon sign comprising a support, a pair of spaced terminals carried by said support, a plurality of neon units each having a pair of insulated sockets and a neon tube connecting said sockets, means for separately adjusting the position of each of said sockets on said support, longitudinally extensible flexible conductors connecting adjacent sockets of adjacent units and connecting said terminals and sockets adjacent thereto, and a trough-like insulator fixed to said support and separating said conductors from adjacent uninsulated parts of the sign.

2. A neon sign comprising a support, a pair of spaced terminals carried by said support, a plurality of neon units each having a pair of insulated sockets and a neon tube connecting said sockets, means for mounting each of said sockets on said support for separate adjustment in perpendicular directions, longitudinally extensible flexible conductors connecting adjacent sockets of adjacent units and connecting said terminals and sockets adjacent thereto, and a trough-like insulator fixed to said support and separating said conductors from adjacent uninsulated parts of the sign.

THOMAS HENRY BOLAND.
RICHARD CLIFTON ARNOLD.
